UNITED STATES PATENT OFFICE.

SHIRLEY SCOTT, OF WAKENDA, MISSOURI.

ANCHOR RIPRAP.

Application filed December 3, 1923. Serial No. 678,252.

To all whom it may concern:

Be it known that I, SHIRLEY SCOTT, a citizen of the United States, residing at Wakenda, in the county of Carroll and State of Missouri, have invented certain new and useful Improvements in Anchor Ripraps, of which the following is a specification.

This invention relates to an improvement in rip raps and has more particular reference to a means adapted to be positioned at the banks of rivers or streams and wherein sand and silt will be collected in a more expeditious manner than is now possible with other rip raps used for this purpose, the primary object of the invention residing in the provision of such a device or article that may be manufactured and set up at a cost considerably less than is now possible.

With the above and other objects in view as the nature of the invention will be better understood, the same comprises the novel form, combination and arrangement of parts hereinafter more fully described, shown in the accompanying drawing and claimed.

In the drawing wherein like reference characters indicate corresponding parts throughout the different views,

Figure 1 is a side elevational view of an anchor rip rap constructed in accordance with the present invention,

Figures 2 and 3 are detail transverse sectional views taken substantially upon the lines 2-2 and 3-3 respectively of Figure 1, and

Figure 4 is an end elevational view of the rip rap shown in the other figures.

Now having particular reference to the drawing, my novel rip rap comprises preferably four equally spaced substantially triangular shaped members designated respectively, 5, 6, 7 and 8, which triangular shaped members are rigidly joined together in a manner hereinafter to be more fully described.

The construction of each of these substantially triangular shaped members is relatively the same and a description of one will suffice for all. As clearly shown in the detailed views, Figures 2, 3 and 4, each of said substantially triangular shaped members comprise a pair of cross bars 9 that are formed at their opposite ends with openings for allowing a length of steel wire 10 to be guided therethrough. Suitably connected at

their opposite ends to the vertical and transverse portions of said strip of wire 10 are cross wires 11 which forms a wire mesh screen, it being noted that the screens of the substantially rectangular shaped members 6 and 7 are of relatively wide mesh for allowing the sand and silt to pass therethrough while the screens of the end rectangular members 5 and 8 are of very fine mesh for preventing the passage of the sand or silt outwardly through the ends of the rip rap.

Interconnecting the members 5 to 8 inclusive, is a pair of longitudinal boards 12, it being noted from a consideration of Figures 2, 3 and 4, that these boards are secured to the cross bars 9-9 of each of the frame members at opposite sides of their point of crossing and are secured thereto in any manner desirable, such as by nails, staples or the like.

Threaded through openings at the central point of each of the members 5 to 8 is a longitudinal wire 13 while also threaded through the openings at opposite ends of the cross members 9-9 are other wires 14.

Certain ends of the wires 13 and 14 are connected to the end member 8 while the opposite ends thereof extend beyond the opposite end member 5 and are platted together at 15 for providing a cable whereby the rip rap thus formed may be anchored to the bottom of the river or stream.

It will thus be seen that I have provided a highly novel and useful form of rip rap and one wherein the sand and silt will be more expeditiously formed at the shore of the body of water for thereby preventing the shore from becoming cracked or washed away by the action of the water thereon.

Although I have herein set forth the most practical embodiment of this invention with which I am at this time familiar, it is nevertheless to be understood that minor changes may be made in the invention without departing from the spirit and scope of the appended claim.

Having thus described my invention, what I claim as new and desire to secure by Letters Patent is:—

A rip rap anchor structure including in combination, a plurality of pairs of bars, the bars of each pair being arranged in cruciform relation and secured to each other at

points of intersection, spacing boards secured at intervals to the bars of each pair and disposed one at each side of the points of the connection between the bars, screens disposed on the pairs of bars, and cables trained through the end portions of the bars and bridging the spaces between the pairs of

bars and having end portions extending beyond one of the terminal pairs of bars and both together to form an anchor line for the structure. 10

In testimony whereof I affix my signature.

SHIRLEY SCOTT.
